UNITED STATES PATENT OFFICE

160,746

CERTIFICATE HOLDER

Joseph M. Schumann, Inglewood, Calif., assignor to Semco Research, Inc., Inglewood, Calif.

Application July 19, 1949, Serial No. 3,992

Term of patent 14 years

(Cl. D14—6)

To all whom it may concern:

Be it known that I, Joseph M. Schumann, a citizen of the United States and a resident of Inglewood, in the county of Los Angeles and State of California, have invented a new, original, and ornamental Design for a Certificate Holder, of which the following is a specification, reference being had to the accompanying drawing, forming a part thereof.

I claim:

The ornamental design for a certificate holder, substantially as shown and described.

JOSEPH M. SCHUMANN.
